US0D1085091S

(12) **United States Design Patent** (10) Patent No.: **US D1,085,091 S**
(45) Date of Patent: ** Jul. 22, 2025

(54) **DATA PROCESSING DEVICE**

(71) Applicant: **YANDEX EUROPE AG**, Lucerne (CH)

(72) Inventors: **Andrey Olegovich Korolenko**, Moscow (RU); **Andrey Alekseevich Blokhin**, Moscow (RU); **Oleg Valerevich Fedorov**, Moscow (RU); **Igor Iurevich Znamenskii**, d Drozhzhino (RU); **Ivan Vladimirovich Prostov**, Moscow (RU); **Vladimir Viktorovich Khulagov**, Balashikha (RU); **Aleksandr Alekseevich Konovalov**, mkr Opalikha (RU); **Konstantin Aleksandrovich Klubnichkin**, Moscow (RU); **Nikita Aleksandrovich Vedeneev**, Moscow (RU)

(73) Assignee: **Y.E. Hub Armenia LLC**, Yerevan (AM)

(**) Term: **15 Years**

(21) Appl. No.: **29/730,135**

(22) Filed: **Apr. 1, 2020**

(30) **Foreign Application Priority Data**

Feb. 14, 2020 (RU) 2020500649

(51) LOC (15) Cl. **14-02**

(52) U.S. Cl.

USPC **D14/439**

(58) **Field of Classification Search**

(57) CLAIM

The ornamental design for a data processing device as shown and described.

DESCRIPTION

FIG. 1 is a top front left perspective view of a data processing device, in accordance with a first embodiment of the present design.

FIG. 2 is a bottom rear right perspective view of the data processing device, in accordance with the first embodiment of the present design.

FIG. 3 is a front elevation view of the data processing device, in accordance with the first embodiment of the present design.

FIG. 4 is a rear elevation view of the data processing device, in accordance with the first embodiment of the present design.

FIG. 5 is a right elevation view of the data processing device, in accordance with the first embodiment of the present design.

FIG. 6 is a left elevation view of the data processing device, in accordance with the first embodiment of the present design.

FIG. 7 is a top plan view of the data processing device, in accordance with the first embodiment of the present design; and,

FIG. 8 is a bottom plan view of the data processing device, in accordance with the first embodiment of the present design.

FIG. 9 is a top front left perspective view of the data processing device, in accordance with a second embodiment of the present design.

FIG. 10 is a bottom rear right perspective view of the data processing device, in accordance with the second embodiment of the present design.

FIG. 11 is a front elevation view of the data processing device, in accordance with the second embodiment of the present design.

FIG. 12 is a rear elevation view of the data processing device, in accordance with the second embodiment of the present design.

FIG. 13 is a right elevation view of the data processing device, in accordance with the second embodiment of the present design.

FIG. 14 is a left elevation view of the data processing device, in accordance with the second embodiment of the present design.

FIG. 15 is a top plan view of the data processing device, in accordance with the second embodiment of the present design.

FIG. 16 is a bottom plan view of the data processing device, in accordance with the second embodiment of the present design.

FIG. 17 is a top front left perspective view of the data processing device, in accordance with a third embodiment of the present design.

FIG. 18 is a bottom rear right perspective view of the data processing device, in accordance with the third embodiment of the present design.

FIG. 19 is a front elevation view of the data processing device, in accordance with the third embodiment of the present design.

FIG. 20 is a rear elevation view of the data processing device, in accordance with the third embodiment of the present design.

FIG. 21 is a right elevation view of the data processing device, in accordance with the third embodiment of the present design.

FIG. 22 is a left elevation view of the data processing device, in accordance with the third embodiment of the present design.

FIG. 23 is a top plan view of the data processing device, in accordance with the third embodiment of the present design. FIG. 24 is a bottom plan view of data processing device, in accordance with the third embodiment of the present design. FIG. 25 is a top front left perspective view of the data processing device, in accordance with a fourth embodiment of the present design.

FIG. 26 is a bottom rear right perspective view of the data processing device, in accordance with the fourth embodiment of the present design.

FIG. 27 is a front elevation view of the data processing device, in accordance with the fourth embodiment of the present design.

FIG. 28 is a rear elevation view of the data processing device, in accordance with the fourth embodiment of the present design.

FIG. 29 is a right elevation view of the data processing device, in accordance with the fourth embodiment of the present design.

FIG. 30 is a left elevation view of the data processing device, in accordance with the fourth embodiment of the present design.

FIG. 31 is a top plan view of the data processing device, in accordance with the fourth embodiment of the present design; and,

FIG. 32 is a bottom plan view of the data processing device, in accordance with the fourth embodiment of the present design.

The broken lines showing additional structure of the data processing device form no part of the claimed design.
